UNITED STATES PATENT OFFICE.

AUGUST H. WIRZ AND AUGUST V. W. RAUSCH, OF PHILADELPHIA, PENNSYLVANIA; SAID RAUSCH ASSIGNOR TO SAID WIRZ.

MACHINE FOR MAKING PILLS, TABLETS, &c.

SPECIFICATION forming part of Letters Patent No. 298,328, dated May 6, 1884.

Application filed October 30, 1883. (No model.)

To all whom it may concern:

Be it known that we, AUGUST H. WIRZ and AUGUST V. W. RAUSCH, citizens of the United States, residing at Philadelphia, in the county 5 of Philadelphia and State of Pennsylvania, have invented certain new and useful Improvements in Machines for Making Pills, Tablets, &c., of which the following is a specification, reference being had therein to the accompanying drawings.

Our invention relates to machines for automatically forming pills, &c., by compressing a sufficient quantity of the pulverized material into the required shape; and the improvement 15 consists in the manner of constructing said machine, as will be hereinafter described, and more particularly pointed out in the claims.

The principal operating parts of our machine are, first, a magazine or hopper for holding the powdered material from which the pills are to be made; second, a rectangular sliding plate having at or near one or both of the ends thereof a gage for measuring the powdered material to be used in forming each pill; 25 third, a hollow steel cylinder into which the powder is emptied after being gaged or measured; fourth, two solid cylindrical steel plungers, set one above the other, the lower one fitting into the bottom and the upper one into 30 the top of the steel cylinder. The upper plunger being withdrawn from the steel cylinder, the powdered material is dropped therein, after which the top plunger is forced downward, and the pill is compressed into the desired 35 shape between the upper and lower plungers, the steel cylinder keeping the material in position to be acted upon by the plungers.

In the accompanying drawings, Figure 1 is a front elevation of our machine; Fig. 2, a rear 40 elevation; Fig. 3, an end elevation. Fig. 4 is a cross-section through the middle of the machine. These figures all show the machine in position immediately after having formed a pill and before the said pill has been knocked 45 off of the top of the bottom plunger into the receiving-receptacle. Figs. 5 and 6 are details of the upper and lower plungers.

A A represent the frame of the machine.

B is a driving-shaft extending horizontally

across the top of the machine, and having on 50 one end thereof the driving-pulley C.

C is a crank on the shaft B.

c" is a vertical shaft operated by the crank C'.

a' is a knuckle-joint in the shaft c", to allow 55 said shaft to be operated by the crank.

d is a horizontal brace or support extending across the machine, and forming a guide or bearing for the vertical shaft.

k is a cylindrical steel plunger secured in the lower end of the shaft c". 60

b is a cam on the shaft B.

a₁ and a₂ are notches on the cam b.

b" is a cam on the outer end of the shaft B.

a is a wheel or pulley on the shaft B.

g is a magazine or hopper into which the 65 powder is placed.

g' is a wire screw extending downward into the hopper for the purpose of keeping the powder loose, so that it will drop or fall freely. This screw is operated by a belt extending 70 from the pulley a to a wheel on the shaft carrying the said screw.

D is a rectangular slide moving back and forward under the hopper.

d" is a hole in the end of the slide D. This 75 hole serves as a gage or measure for the amount of powder to be used in making each pill. There may be an additional hole of a different size in the opposite end of the slide D, said slide being turned end for end when desiring 80 to change the size of the pill.

k' is the bottom plunger. This plunger enters the steel cylinder from the lower end and is never entirely removed therefrom.

h' is a guide and support for the plunger k'. 85

h is a set-screw in the bottom of the guide h', to regulate the distance the lower plunger will drop down in the cylinder h.

c is a lever pivoted at or near the middle thereof. The upper end of this lever works 90 on the cam b, and the lower end is connected to the lever c₁, which is connected with the lever c₂, fastened rigidly to the horizontal shaft m, secured under the bed-plate of the frame.

c₃ is an arm or lever fastened on the shaft 95 m, and extending up into a slot or opening cut in the slide D.

- n* is a spiral spring fastened to the lever *c*, and connecting with any rigid or stationary part of the machine. This spring is for the purpose of keeping the upper end of the lever 5 *c* always in position against the cam *b*.
*b*₂ is a pivoted bar or lever operated by the vertical sliding bar *b*, and extending into the slot *s* in the middle of the lower plunger.
n' is a spiral spring fastened at one end to 10 the lever *b*₂ and at the other to the support *h*. This spring draws down the lever *b*₂, thus bringing the lower plunger back into position after it has been forced upward.
d is a vertical bar extending downward 15 through the support *d*.
e is a catch or projection on the side of the bar *d'*. This catch is operated upon by a similar projection extending about one-fifth of the way around on the side of the collar *b'*.
20 *e'* is a spiral spring wound around the bar *d'*, and having one end secured thereto and the other end fastened to the support *d*. This spring serves to bring the bar back into position after being partially turned around by 25 the projection on the collar *b'*, operating on the catch *e*.
d is a finger on the lower end of the bar *d'*. This finger is adjusted so that it will pass over the top of the bottom plunger and knock the 30 finished pill off into a receptacle placed to receive it.
The machine having finished making a pill, and being in the position shown in Fig. 1, 2, 3, and 4, with the pill resting on the top of 35 the bottom plunger and the finger *d*, as shown in Fig. 1, the powdered material will fall down through the opening in the bottom of the hopper into the gage or measure *d''* on the slide D. (See Fig. 4.) The wheel C, being then 40 turned, moves the shaft B, thus operating the various cams, levers, &c. The projection on the side of the collar *b'* will immediately operate on the catch *e*, causing the shaft *d'* to turn partially around and throw the finger *d*, 45 forward, thus knocking off the finished pill resting on the end of the lower plunger. Immediately after the finger *d*, has been thrown forward, the cam *b* operates the lever *c*, which, acting through the levers *c*, *c*₂, and *c*₃, moves 50 the slide D forward, so as to bring the gage or measure *d''* directly over the hollow cylinder *h*, into which the powder drops, the bottom plunger, *k'*, having in the meantime dropped down sufficiently far in the cylinder 55 to allow the material to enter. By the continued revolving of the shaft B after the powder has been dropped into the cylinder, the crank C moves the shaft *c''*, carrying the plunger *k* down into the cylinder *h*, thus compressing the powder between the ends of the upper and lower plungers. Immediately after the pill has been thus formed, the upper

plunger moves or is carried upward, and the slide D recedes, followed by the finger *d*, until both the slide and the finger are in the position shown in the figures. In the meantime the lower plunger is, by means of the cam *b''*, operating on the bar *b*, and lever *b*₂, forced upward, carrying the completed pill on the end into a position to be knocked off by the finger *d*. (See Fig. 1.) The notches *a*, on the cam *b* (see Fig. 3) cause the lever *c* to shake the slide D back and forward when the measure is under the hopper, thus insuring a full charge. The notches *a*, cause a similar shaking motion to the slide D when it is over the cylinder *h*, and by this means prevents any powder from remaining in the measure. The form of the pill is regulated by the shape of the ends of the plungers *k* *k'*, and if 80 the ends of said plungers are cut squarely off a circular tablet will be formed.

Having thus described our invention, what we claim as new, and desire to secure by Letters Patent of the United States, is—

1. In a pill or tablet compressing machine, the shaft B, having thereon the crank C', cams *b* and *b''*, in combination with the pivoted lever *c*, operated by the cam *b*, and thus moving the sliding gage D, the vertical sliding bar *b*, the lever *b*₂, operating the lower plunger, *k'*, and the shaft *c''*, carrying the upper plunger, *k*, all substantially as and for the purpose described.

2. In a pill-compressing machine, the shaft B, connected with suitable operating means, and having thereon the crank C', cams *b* *b''*, in combination with the shaft *c''*, having the plunger *k*, the sliding gage or measure D, operated by the lever *c*, the plunger *k'*, operated by the vertical sliding bar *b*, and the cylinder *h*, all substantially as shown.

3. In a pill-compressing machine, the plungers *k* *k'*, operating from opposite directions in the hollow cylinder *h*, the sliding gage D, in combination with the magazine *g*, the bar *d'*, having the finger *d*, and driving-shaft B, all substantially as shown.

4. In a pill or tablet compressing machine, the plungers *k* *k'*, operating toward each other from opposite directions, and the hollow cylinder *h*, in combination with the finger *d*, connected with suitable operating mechanism for moving the said finger back and forward, thus knocking the finished pill or tablet from off 110 the top of the lower plunger, substantially as shown.

In testimony whereof we affix our signatures in presence of two witnesses.

AUGUST H. WIRZ.

AUGUST V. W. RAUSCH.
